(57) **CLAIM**

The ornamental design for a wireless heart monitor, as shown and described.

DESCRIPTION

FIG. 1 is a perspective view of a wireless heart monitor, showing our new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a perspective view thereof, in which electrodes are shown separated; and,

FIG. 10 is an enlarged view of portion 10 shown in FIG. 1. The even length broken lines depict portions of the article that form no part of the claimed design. The uneven length broken lines in FIGS. 1 and 10 are for the purpose of showing the bounds of the FIG. 10 enlarged view and form no part of the claimed design.
